UNITED STATES PATENT OFFICE.

LOUIS L. BENTLEY, OF BEAVER FALLS, PENNSYLVANIA, ASSIGNOR TO ARMSTRONG CORK COMPANY, OF PITTSBURGH, PENNSYLVANIA, A CORPORATION OF PENNSYLVANIA.

METHOD OF TREATING GRANULATED CORK.

1,184,307.

Specification of Letters Patent. Patented May 23, 1916.

No Drawing.

Application filed November 25, 1914. Serial No. 873,964.

To all whom it may concern:

Be it known that I, LOUIS L. BENTLEY, a citizen of the United States, and a resident of Beaver Falls, in the county of Beaver 5 and State of Pennsylvania, have invented a new and useful Method of Treating Granulated Cork, of which the following is a full, clear, and exact description.

My invention relates to the making of 10 granulated cork into cement blocks or articles, and is designed to improve present methods by obtaining a larger expansion of the cork under treatment, thus giving more volume of product, and also to avoid liability to burning or charring of the 15 granules.

A further object is to improve the insulating qualities of the cork block or article by decreasing its specific gravity and increasing the cell formation therein. 20

In carrying out my invention, I place the natural granulated cork in a closed, airtight vessel, and then exhaust the air therefrom to give a partial vacuum; this vacuum 25 preferably being carried out as far as ordinary commercial vacuum methods apply or are practicable. The cork is then heated in the vessel, preferably being agitated during heating by rotating the vessel 30 or giving it some movement. The heating is carried to a point where pressure is accumulated in the vessel, due to the formation of steam from the natural moisture and vapors in the cork. As an example, heating 35 may be continued until a pressure is generated of thirty to a hundred pounds or more. After this heating and obtaining of pressure, the pressure is suddenly released, causing an expansion of the cells to such an extent that the specific gravity may be 40 reduced about 50%, with a corresponding increase in the volume of the cork, provided space is allowed for expansion.

If the vessel is practically filled with 45 granulated cork, thus preventing any material expansion, the cork will tend to expand somewhat during the application of heat and pressure, and when the pressure is suddenly released, the sudden expansion of 50 the cells will cause an expansive action between the cells, thus cementing and compressing the granules together and forming the article in place. In other words, in such case, the natural expansion on the release of 55 pressure is prevented and results in a com-

pression of the granules into a cemented article. By this method of cementing under the heat and pressure following the vacuum, the resinous materials of the cork are all retained within the mass, thus utilizing 60 them fully for their cementing action between the granules and cells.

Following the heating of the cork within the vacuum receptacle, I also preferably introduce superheated steam under pressure 65 of, for example, 180 pounds, with a temperature of 750 degrees Fahrenheit; the sudden release of pressure following or succeeding the application of superheated steam. The heat will be disseminated throughout the 70 mass by reason of the steam generated within the mass, and this will be further carried out by the superheated steam admitted, if this step is also used.

If it is desired to obtain the maximum 75 expansion or expanding tendency for the cork, when the pressure is released, a vacuum or partial vacuum may again be applied to the receptacle, thus increasing the expansive action. 80

The advantages of my invention result principally from the sudden release of pressure which gives a strong, puffing or expanding tendency in the cells of the cork, thus increasing the volume if the contents 85 are allowed to shoot out from the vessel or fill only a part of the vessel; while if they substantially fill the vessel, a strong compressive cementing action is obtained. A further advantage flows from the use of the 90 vacuum or partial vacuum which largely prevents the action of the air upon the material contained.

Many changes may be made in the form and apparatus used and the steps of the 95 process without departing from my invention.

I claim:

1. The method of treating cork, which consists in inclosing cork granules in an 100 inclosing vessel, applying heat to the vessel and thereby setting up a pressure within the confined mass due to the vaporization of moisture and other vaporizable materials contained in the cork, and then suddenly 105 releasing the pressure to cause an expansion of the said particles; substantially as described.

2. The method of treating granulated cork, consisting in inclosing it within an 110

- air-tight vessel, applying a vacuum or partial vacuum, setting up pressure therein by heating the cork, and then suddenly releasing the pressure, substantially as described.
- 5 3. The method of treating granulated cork, consisting in heating it within a vessel in which a partial vacuum is formed, substantially as described.
- 10 4. The method of treating granulated cork, consisting in inclosing it within a receptacle, setting up pressure therein by heating the cork, admitting a heating fluid, such as superheated steam, and then suddenly releasing the pressure, substantially as described.
- 15 5. The method of treating granulated cork, consisting in feeding it into an air-tight receptacle, setting up at least a partial vacuum therein, heating the cork to set up pressure within the receptacle, feeding a hot fluid such as superheated steam into the receptacle, and suddenly releasing the pressure, substantially as described.
- 20 6. The method of treating cork, which consists in inclosing cork granules in an inclosing vessel, applying heat to the vessel and thereby setting up a pressure within the confined mass due to the vaporization of moisture and other vaporizable materials contained in the cork, then suddenly releasing the pressure to cause an expansion of the said particles, and then forming a partial vacuum in said vessel to cause a further expansion of the cork particles; substantially as described.
- 25 7. The herein described method of treat-

ing cork, which consists in inclosing cork granules within an inclosing vessel, creating a partial vacuum within said vessel, applying heat to the vessel to thereby set up a pressure within the confined mass due to the vaporization of the moisture and other vaporizable material contained in the cork, and then suddenly releasing the pressure; substantially as described.

45

8. The herein described method of treating cork, which consists in inclosing cork granules within an inclosing vessel, creating a partial vacuum within said vessel, applying heat to the vessel to thereby set up a pressure within the confined mass due to the vaporization of the moisture and other vaporizable material contained in the cork, then suddenly releasing the pressure, and then again creating a partial vacuum in said vessel; substantially as described.

55

9. The method of treating cork, which consists in inclosing cork granules in an inclosing vessel in which they are capable of limiting the expansion applying heat to the vessel to thereby set up a pressure within the confined mass, and then suddenly releasing the pressure and utilizing the sudden expansion of the cork particles within the confined space to thereby cement them together; substantially as described.

65

In testimony whereof, I have hereunto set my hand.

LOUIS L. BENTLEY.
